(57) **CLAIM**

What is claimed is the ornamental design for a CD desktop clock, as shown and described.

DESCRIPTION

FIG. 1 is a front perspective view of one embodiment of the present invention.

FIG. 2 is a rear view thereof.

FIG. 3 is a right side elevational view thereof.

FIG. 4 is a left side elevational view thereof.

FIG. 5 is a top plan view thereof; and,

FIG. 6 is a bottom plan view thereof.

The broken line showing of a battery is for illustrative purposes only and forms no part of the claimed design.
